ATTORNEY

UNITED STATES PATENT OFFICE.

ALFRED SAUTER AND LEO SAUTER, OF CHICAGO, ILLINOIS.

PRINTER'S QUOIN.

1,395,149.

Specification of Letters Patent. Patented Oct. 25, 1921.

Application filed March 13, 1920. Serial No. 365,534.

To all whom it may concern:

Be it known that we, ALFRED SAUTER and LEO SAUTER, citizens of the United States, residing at Chicago, in the county of Cook and State of Illinois, have invented new and useful Improvements in Printers' Quoins, of which the following is a specification.

This invention relates to a printer's quoins and has for its primary object the construction of a quoins of two companion members 10 permanently associated in such a manner that a quick adjustment may be accomplished.

An object of the invention is to permanently connect the two members of a quoins in such a manner that they will coöperate in a most active manner.

A feature of our invention is providing each member with a tongue engaging the groove in the other member in combination 20 with a pin so disposed that the device will be prevented from being disengaged from the groove while at the same time allow accurate adjustment of the quoins.

Besides the above our invention is distinguished in a quoins that can be quickly adjusted for saving time.

With these and other objects in view the invention will be better understood from the following detailed description taken in connection with the accompanying drawing wherein—

Figure 1 is a side elevation of the quoins in collapsed position.

Fig. 2 is a view of the quoins in adjusted position.

Fig. 3 is a plan view of the quoins.

Fig. 4 is a bottom plan view of the upper members.

Fig. 5 is a plan view of the lower member.

Fig. 6 is a longitudinal sectional view.

Fig. 7 is a sectional view on line 7—7 of Fig. 6.

Again referring to the drawing illustrating one construction of our invention the 45 numeral 1 designates a quoins in its entirety consisting of a pair of companion members 2 and 3. Each member is provided with a rib 4 terminating short of one end thereof

and slidably engaging a groove 5 in the other member. Each groove is arranged at a different level than the rib but extends in the same direction and forms projections 5^b 50 slidable on the opposite sides of the associated rib 4. The members are of wedge shape formation so that their inclined surfaces 6 sliding in engagement with each other will cause the thickness of the quoins to increase, as clearly shown in Fig. 2, so as to make the proper adjustments. Recesses 7 are illustrated for engagement with the ordinary tool. For the purpose of preventing complete dislocation between the device and groove we provide a headed pin 8 fixed to one member and engaging a T shaped slot 9 in the other member.

From the foregoing description taken in connection with the accompanying drawing it will be apparent that we provide a device of simple construction that may be readily adjusted and in which the parts are permanently associated so as to insure the co-operation of two members accurately associated so as to accomplish accurate adjustment.

It is, of course, to be understood that the 75 invention may be constructed in various other manners and the parts associated in different relations and, therefore, we do not desire to be limited in any manner except as set forth in the claim hereunto appended.

Having thus described our invention, what we claim is—

A printer's quoins comprising two wedge shaped members each provided with a rib terminating short of one end and each groove 85 arranged at a different level but extending in the same direction as the rib, the groove of one member slidably receiving the rib of the other member, and projections on each member slidably engaging the side of its associated groove, each member being further provided with tool receiving recesses.

In testimony whereof we affix our signatures.

ALFRED SAUTER.
LEO SAUTER.
